CLOTHES HANGER

Waino K. Latvala, New York, N. Y.

Application January 31, 1947, Serial No. 725,550

3 Claims. (Cl. 223—88)

1

My invention relates to clothes hangers and more particularly to clothes hangers adapted to support a coat, a vest and trousers.

The object of my invention is to provide a clothes hanger of the character indicated above and adapted to prevent trousers supported thereby from sliding off the hanger without the use of any clamping means.

Other objects of my invention may appear in the following specification describing my invention with reference to the accompanying drawing illustrating some preferred embodiments of my invention.

It is to be understood, however, that my invention is not to be limited or restricted to the exact construction and combination of parts described in the specification and shown in the drawing, but that such changes and modifications can be made, which fall within the scope of the claims appended hereto.

In the drawing:

Figure 1 is an elevational front view of the clothes hanger according to my invention.

Figure 2 is an elevational end view of the clothes hanger shown in Figure 1, a pair of trousers hanging on the hanger being shown fragmentarily.

Figure 3 is a front view of Figure 2.

Figure 4 is an elevational front view of a modified form of the clothes hanger shown in Figure 1, and

Figure 5 is an elevational front view of another modified form of the clothes hanger according to my invention.

Referring now in detail to the drawing the clothes hanger forming the subject matter of my invention is preferably made from one continuous piece of strong wire.

The wire starts with a short straight portion 10 extending horizontally to the right ending in a sharp upwardly curved portion 11. From this a shoulder piece 12 extends in a shallow curve toward the left. On the end of this shoulder piece the wire is doubled upon itself, twisted to form an upwardly extending neck 13 and a hook 14, which is open on its left end, so that it can be suspended on a rod or the like in a clothes closet.

From the neck 13 the wire extends in a shallow downward curve to the left to form a second shoulder piece 15 ending in a sharp curve 16 connecting the second shoulder piece 15 with a horizontal extending portion 17 extending horizontally toward right. This straight wire portion ends in a sharp curve 18, located a short

2

distance below the short straight wire portion 10 and continuing in a second horizontal portion 19 extending horizontally toward the left somewhat beyond the center of the horizontal extending portion 17 and a short distance below this wire portion.

The two shoulder pieces 12 and 15 serve the purpose to support a vest and a coat. A pair of trousers 20 is folded over approximately at knee length and slipped onto the horizontal extending portion 17, so that the lower and shorter second horizontal portion 19 contacts the trousers 20 on the outside and prevents them from slipping from the horizontal extending portion 17.

If desired the clothes hanger can be formed to support more than one pair of trousers. In that case, the sharp downward curve 18 connects the horizontal extending portion 17 with another straight wire portion 21 ending on its left end in another sharp downward curve 22 continuing horizontally toward the right in a third straight wire portion 23. This may be continued as often as desired to form five, six or more trouser supporting straight wire portions. The last straight wire portion 24 is shorter, similar to the wire portion 19 described above and the trousers are placed and secured on the several trouser supporting straight wire portions, 21, 23, etc. as described above.

In Figure 5 another modified form of the clothes hanger according to my invention is shown. This form is similar to the form shown in Figure 4, but each additional trouser support consists in this case of two strands of wire 21^a and 21^b, 23^a and 23^b etc., arranged so close to each other, that the two strands of each trouser support exert enough friction on the trousers placed between them to prevent accidental removal of said trousers. Each additional trouser support is connected with the support above by a curved wire portion 22^a.

While the clothes hanger forming the subject matter of my invention has been described as being made from wire, it is to be understood, that it may be formed and made from plastic or any other suitable material.

Having described my invention, I claim as new and desire to secure by Letters Patent:

1. As a new article of manufacture, a clothes hanger fabricated solely of a single continuous piece of material, and comprising a bow-shaped portion adapted to support a vest and coat and having one end portion inturned, a horizontal extending portion adapted to support trousers thereon arranged in the same plane as said bow-

shaped portion and secured to the other end of said bow portion, the opposite end portion of said horizontal portion being spaced from the inturned end portion of said bow portion and bent upon itself so as to terminate in a second horizontal portion of a length less than the first-named horizontal portion, and spaced from the latter, there being intermediate the first-named horizontal portion and second-named horizontal portion a plurality of further horizontal portions of a length corresponding to the first-named horizontal portion, and equally-spaced from each other, the second and further horizontal portions all lying in the same plane as said first-named horizontal portion.

2. As a new article of manufacture, a clothes hanger fabricated solely of a single continuous piece of material, and comprising a bow-shaped portion adapted to support a vest and coat and having one end portion inturned, a horizontal extending portion adapted to support trousers thereon arranged in the same plane as said bow-shaped portion and secured to the other end of said bow portion, the opposite end portion of said horizontal portion being spaced from the inturned end portion of said bow portion and bent upon itself so as to terminate in a second horizontal portion of a length less than the first-named horizontal portion, and spaced from the latter, there being intermediate the first-named horizontal portion and said second-named horizontal portion a plurality of further horizontal portions of a length corresponding to the first-named horizontal portion, the second and further horizontal portions all lying in the same plane as said first-named horizontal portion,

every other portion of said plurality of horizontal portions being arranged in close proximity to the adjacent horizontal portion and adapted to frictionally engage a pair of trousers thereon.

5. As a new article of manufacture, a clothes hanger fabricated solely of a single continuous piece of material, and comprising a bow shaped portion adapted to support a vest and coat and having one end portion inturned, a plurality of horizontal extending portions adapted to support trousers thereon arranged in the same plane as said bow shaped portion and having one end secured to the other end of said bow portion, the other end portion of said horizontal portions being spaced from the inturned end portion of said bow portion and bent upon itself so as to terminate in a second horizontal portion of a length less than the first named horizontal portions and spaced from the latter, the second horizontal portion lying in the same plane as said first named horizontal portions.
